MAGAZINE-OPERATED SAFETY FOR
AUTOMATIC FIREARMS

Bonifacio Guisasola, Eibar, Spain

Application August 26, 1947, Serial No. 770,724

4 Claims. (Cl. 42—70)

1

This invention relates to an improved automatic safety-device for automatic pistols.

Most automatic firearms, and more particularly pistols, will retain, after being fired, a loaded cartridge within the breech chamber. Although in such a case the cartridge magazine may be extracted from the weapon, the retained cartridge might still discharge, usually as the result of carelessness. The consequences of such accidents are but too well known.

Previous attempts to remedy this undesirable feature have been ineffective, mainly because they have not fulfilled the primary requirements that the desired safety mechanism operate positively and automatically; and without need of supplementary manipulation.

The principal object of this invention, therefore, is to provide such an automatic safety device.

As hereinafter more particularly described, the device comprises a substantially cylindrical body, provided with grooves and projections with which to attach it to the firearm within a transverse housing provided just above the trigger mechanism, which body automatically blocks or frees the trigger, as the case may be, when the magazine is disengaged from, or introduced into, its tube, all without attention from the user.

The invention will be more clearly understood when considered with reference to the annexed drawings, forming part of this specification, and illustrating by way of example and not of limitation a preferred embodiment.

In these drawings:

Fig. 1 is a right side view of the new and improved safety-device as adapted to a firearm.

Fig. 2 is a front view of the device, when the magazine is fully inserted in the magazine tube, and the trigger is unimpeded, and in dotted lines the position of the safety-device when the magazine is out and the trigger is stopped.

Fig. 3 is a front view of the cylindrical body, that is the principal component of the safety-device.

Fig. 4 is a vertical section of the cylindrical body, taken along the line IV—IV of Fig. 3.

Fig. 5 is a vertical section of the cylindrical body, taken along the line V—V of Fig. 3.

Fig. 6 is a diagrammatic plan of Fig. 2.

Fig. 7 is a side view of Fig. 6.

Fig. 8 is a side view of a holding pin and lock used with the cylindrical body.

Fig. 9 is a side view of a cylindrical spring used with the holding pin of Fig. 8.

The safety-device forming the object of this

2

invention comprises a substantially cylindrical main body 1, formed at one of its ends with a reduced cylindrical neck 2 concentric therewith. At the other end of the body 1, and integral therewith, is a semi-cylindrical boss 3 provided with a radially projecting arm 4. The lower end of the arm 4, near the boss 3, has an inclined surface 5 against which the magazine 7 may slide. The central fore part of the body 1 has a curved, nearly vertically, deviated recess 6 (Figs. 3 and 5) to movably fit the back face of the magazine 7. The central under part of the body 1 is provided with a rectangular horizontally-directed trigger way 8 (Figs. 3 and 8) with vertical sidewalls 9, to enable the trigger 21 to reach the discharge releasing panel (not shown).

The body 1 has a longitudinal bore 10 eccentric to its axis, with an opening from the right side, as viewed in Fig. 6, and terminating in an end wall 17. The body 1 also has a longitudinal groove 11 extending half its length and merging downwardly into the bore 10. It has a transversal groove 12, extending from the base of the arm 4 to the longitudinal groove 11 (Fig. 6) and likewise communicating with the longitudinal bore 10.

To maintain the safety-device in operative position, a cylindrical holding pin 13 (Fig. 8), having a head 14 and lock 15, is adapted to slidably engage the bore 10 and grooves 11 and 12, respectively. The head 14 has an annular face 16 on the side facing the pin 13, and the helical spring 18 is designed to encircle the pin 13 and abut the face 16. Hence, when the pin 13 and spring 18 are assembled with the body 1, the spring 18 is compressed between the annular face 16 and the end wall 17 of the bore 10.

A housing 19 (Figs. 2 and 6) contains these safety elements. The housing 19 is substantially of the same shape as the body 1 and its associated projecting members, and is secured horizontally to the firearm frame 20, above the trigger 21 and within reach of the trigger beak 22. The housing 19 has a cylindrical wall provided with a circular groove 23, which normally receives the lock 15.

The body 1 and associated projecting members can effectuate a slight transverse sliding motion within their housing 19. The reduced cylindrical neck 2 of the body 1 projects through an aperture 24 (Fig. 2) in the firearm frame 20, while the arm 4 moves to the left within a radial recess 25 in the housing 19, thus presenting undesired rotation of the safety-device.

To assemble the safety-device and secure it to the frame 20 of the firearm, the holding pin 13 is

held in the right hand, and the spring 18 is drawn over it with the left hand. Then the body 1 is held in the left hand, and the right hand introduces the pin 13 and spring 18 into the bore 10 in the body 1. The rear face of the head 14 is provided with a slot 26, and this slot 26 is engaged with a screwdriver to compress the spring 18 until the lock 15 enters the groove 11; then the screwdriver is turned counterclockwise until the lock 15 is held within the vertical groove 12 (position A in Fig. 4). The safety-device is now ready to be introduced into the housing 19 of the frame 20, from the right, so that the arm 4 is nested within its complementary recess 25, to the point where the transverse groove 12 of the body 1 coincides with the circular groove 23 of the housing 19 of the frame 20. The screwdriver then rotates the slot 26 clockwise until the lock 15 is again opposite the longitudinal groove 11 (position b in Fig. 4), which is its normal position. The outwardly projecting portion of the lock 15, beyond the cylindrical portion of the body 1, has now engaged the circular groove 23, whereby the holding pin 13 is locked to the frame 20 and the safety device secured in working position. The spring 18, compressed between the immovable annual face 16 and the end wall 17 of the bore 10, which end wall 17 is movable with respect to the pin 13, expands and forces the body 1 toward the left, thereby projecting the reduced portion 2 through the aperture 24, beyond the left wall of the frame 20.

To remove the safety-device, the body 1 is forced to the right by pressing the reduced neck 2 against the left surface of the frame 20, thereby coinciding the grooves 12 and 23 and permitting removing of the safety-device from the frame 20.

In brief, the operation of the device is as follows:

The magazine 7 having been withdrawn, the safety-device occupies the extreme left hand position shown in dotted lines in Fig. 2. As the magazine 7 is introduced, it encounters, near the end of its travel, the arm 4. The inclined surface 5 on the arm 4 acts like a cam and slides along the magazine 7 and toward the right, until the vertical upper half of the arm 4 is in contact with the magazine 7. Since the arm 4 is integral with the body 1, the body 1, under pressure of the spring 18, likewise slides to the right, so that the longitudinal groove 11 moves with respect to the fixed lock 15, and the bore 10 with respect to the fixed head 14 of the pin 13, until the body 1 occupies the extreme right hand position shown in full lines in Fig. 2.

The horizontal trigger way 8 (Fig. 3) is now in a position whereby the beak 22 of the trigger 21 may pass unhindered, so that it can actuate the firing pin.

When the magazine 7 is withdrawn, the pressure against the arm 4 is released, and the body 1 is biased by the spring 18 toward the left, until the left end face 28 of the body 1 engages the opposite face 29 (Fig. 6) of the frame 20. The safety device now again occupies the left hand position shown in dotted lines in Fig. 2. Here a stop 30 (Figs. 2 and 3) on the body 1 projects into the trigger way 8 to block movement of the trigger 21 while the magazine 7 is disengaged. Hence, the firearm cannot be discharged while the magazine 7 is out.

I claim:

1. In an automatic firearm having a removable magazine and a firing mechanism including a

trigger, wherein a cartridge may remain in firing position when the magazine is removed; safety means automatically actuated by removal of the magazine blocking the firing movement of the trigger to fire the cartridge in firing position, said safety means comprising a safety bolt extending transversely of the firearm, yieldable means urging said safety bolt into the firing path of movement of the trigger, and cam means on said bolt cooperating with the magazine when in position moving said bolt out of the path of the trigger.

2. A safety bolt as set forth in claim 1 including in combination therewith a locking pin, a locking finger extending from one side of said pin, said safety bolt being cored to receive said locking pin therewithin and slotted to provide a path of entry to said locking finger, said locking finger extending beyond said locking bolt into a cooperating slot in the firearm, said yieldable means comprising a coil spring located about said locking pin.

3. A safety bolt as set forth in claim 1 comprising a cylindrical member, a reduced cylindrical neck extending from one end of said cylindrical member, the firearm having a complementary shaped recess extending across the path of the magazine and the firing path of the trigger, said cylindrical member being of greater length than the width of the trigger, a cutaway in one side of said cylindrical member of just sufficient width to allow the trigger to move therethrough, said yieldable means moving said bolt laterally to move said cutaway out of registration with trigger path, and a cammed surface on said cylindrical member cooperating with the magazine as it is installed to move said bolt to cause said cutaway to register with the trigger path.

4. In an automatic firearm having a removable magazine and a firing mechanism including a trigger, wherein a cartridge may remain in firing position when the magazine is removed; a safety means blocking the firing movement of the trigger comprising a cylindrical member, a cylindrical neck extending axially from one end of said cylindrical member, the firearm having a lateral recess, complementary to said cylindrical member and neck, intercepting the trigger path and the magazine path, a cutaway in said cylindrical member complementary to a portion of the magazine, another cutaway complementary to the firing path of the trigger, said cylindrical member having an eccentric bore extending longitudinally from the end opposite to the end from which the neck extends, said bore being counterbored, a holding pin complementary to said counterbore having a locking finger extending radially from the larger end of said holding pin, a coil spring about the smaller end of said holding pin arranged to be biased between the end of the small end of the counterbore in said cylindrical member and the shoulder of the larger end of the holding pin, a T-slot in said cylindrical member extending to the larger bore of its counterbore, the head of said T-slot at one end extending to the end of the cylindrical member and arranged to have the locking finger of said holding pin extend therethrough and into a bayonet joint groove in the cylindrical wall of the firearm recess, an arm extending radially from the larger bored end of said cylindrical member into a complementary groove in a wall of the firearm cylindrical recess and intercepting the magazine path, a cam formed on said arm arranged to be contacted by the magazine as it reaches its operative position to move said cylindrical mem-

ber laterally against its spring action and thus bring the trigger cutaway in said cylindrical member into coincidence with the trigger path, the spring serving to move the cylindrical member laterally in the opposite direction when the magazine is removed from contact with the cam arm moving the trigger cutaway out of coincidence with the trigger path causing the cylindrical member to block off the trigger path and prevent firing movement of the trigger.
